United States Patent Office.

JOHN CLEARY, OF BROOKLYN, NEW YORK.

Letters Patent No. 96,310, dated November 2, 1869; antedated October 16, 1869.

IMPROVED THREAD-HOLDER AND CUTTER.

The Schedule referred to in these Letters Patent and making part of the same.

To all whom it may concern:

Be it known that I, JOHN CLEARY, of the city of Brooklyn, in the county of Kings, and State of New York, have invented a new and useful Thread-Holder and Cutter; and I do hereby declare that the following is a full, clear, and exact description of the same, reference being had to the accompanying drawings, which form part of this specification, and in which—

Figure 1 represents a plan view of a thread-holder and cutter constructed according to my invention;

Figure 2 represents an end elevation view of the same; and

Figure 3 represents a transverse section, taken in the line x x , fig. 1.

Similar letters of reference indicate corresponding parts in the several figures.

The object of this invention is to provide for the convenient holding of spools of thread and the cutting of the thread therefrom when needed; and

The invention consists in a novel combination of a spool-stand and spring scissors, whereby the desired end is attained.

Referring to the accompanying drawings—

A is a base, constructed of a block of metal or other material, and of a form as represented, or of other suitable form.

Near the broad end of this base-block A, project two or more fixed cylindrical posts, a a , upon which the spools of thread are placed, and which serve as axles upon which the same may turn.

At the upper extremity of one of these posts, as a' , is hinged or pivoted a supplemental axle, a'' , which locks with the top of the other post a , by means of a tongue upon the one fitting within a groove in the other, so as to serve as a horizontal axle to a third spool.

Projecting upwardly from about the central portion of the base A is a stationary guide, b , through small openings or perforations, in which the thread from each spool is passed, as represented in fig. 1.

At or near the opposite extremity of the base A is a fixed post, B.

Secured to this post B, near its upper extremity,

are fixed and movable blades, O C', the movable blade C' being so pivoted to the fixed blade O as to form a pair of scissors, between which the thread of either spool may be drawn out to a desirable length, and cut at pleasure.

The cutting-edges of the said blades O C', when not being acted upon by a greater force, are held apart by means of a spring, s, attached to the post B, and acting against a rearward projection, e, of the movable blade C, so that the thread may be readily passed between them when it is to be cut.

The movable blade C' is operated by means of a vertical sliding rod, f.

Said rod f is arranged to slide in bearings, e e, attached to the post B, its foot or lower end resting upon the said rearward projection e of the movable blade, so that the downward pressure of the same will cause the closing of the scissors, while its upper end, which extends above the top of the post B, is or may be provided with a button, m, for the more convenient manipulation of the same.

The points or outer extremities of the blades O C' are or may be of a form as represented in fig. 3, for the purpose of facilitating the finding of the interstices between said blades with the thread, and the convenient passage of the same therein.

When desirable, the sliding rod f may be omitted, and the movable blade C' operated by pressing down its rearward projection e, the button m, for convenience of manipulation, being placed thereon instead of the aforesaid rod f, as before described.

What I claim as my invention, and desire to have secured by Letters Patent, is—

The thread-holder and cutter, composed of the vertical spool-axles a a' , with the horizontal axle fitted thereto, as described, the thread-guide b , and the fixed and movable cutting-blades O C', arranged for operation, substantially as herein set forth.

JOHN CLEARY.
